C. F. ADOLPH

MAGNETO MICROPHONIC RELAY

Filed Dec. 21, 1925

Fig. 6.

INVENTOR

Carl Frederick Adolph.

UNITED STATES PATENT OFFICE.

CARL FREDERICK ADOLPH, OF LONDON, ENGLAND, ASSIGNOR TO NEW WILSON ELECTRICAL MANUFACTURING CO. LTD., OF LONDON, ENGLAND.

MAGNETO-MICROPHONIC RELAY.

Application filed December 21, 1925, Serial No. 76,746, and in Great Britain March 31, 1925.

This invention relates to a magneto-microphonic relay of the kind in which a microphone unit whose movable carbon electrode is combined with an armature element, is placed against the magnet poles of a watch receiver so as to be affected by the currents passing through the magnet coils.

The object of the invention is to produce a microphone unit which is of simple construction and which allows of being readily detached for keeping the armature plate and the pole pieces of the magnet free from dust and particles liable to interfere with the free functioning of the diaphragm.

With this object in view the invention consists in the provision of a microphone unit in the form of a bar adapted to bridge the watch receiver and to be retained in position thereon merely by the magnetic attraction.

Preferably the microphone electrodes are accommodated in a casing of U-shaped cross-section whereby they are supported on the watch receiver, and they are controlled by a spring and a screw whereby they can be adjusted within the casing for regulating their position relative to the magnet poles.

A very sensitive microphone is obtained by the employment of a substantially lozenge-shaped armature plate which is fastened by means of its tapering ends to its support.

Fig. 1 of the accompanying drawings represents a sectional view of one form of microphone construction, and

Fig. 2, an inverted plan of the same.

Fig. 3 is a sectional view of a modified form, and

Fig. 4, an end view of the latter.

Fig. 5 is a side view of a further modification, and

Fig. 6 is a perspective view showing the microphone bar and the watch receiver mounted on a stand for use as a sound amplifier in connection with radio receivers.

The microphone is provided, in known manner, with a carbon block *a* between which and a carbon diaphragm *b* a plurality of carbon granules are supported so as to vary the electric resistance between two terminals *c* and *d* under the vibratory movements of the diaphragm *b*. Secured to the outside of the latter is an armature plate *e* which causes the diaphragm plate to vibrate under the influence of the magnetic impulses impressed on a watch receiver *f* against which the microphone is supported with the

armature plate in close proximity to the pole pieces *g* of the receiver magnet.

According to the invention, the microphone unit is constructed as a bar which is adapted to bridge the watch receiver casing and to be held in position on the latter merely by the magnetic attraction. In the construction shown in Figs. 1 and 2, the diaphragm *b* and the armature plate *e* are connected by screws *h* direct to the carbon block *a* which is correspondingly elongated. The block is accommodated in a metal casing *i* of U-shaped cross-section and is controlled in the latter by a screw-spindle *k*, an ebonite nut in the form of a hand-wheel *l* and a blade spring *m* which abuts against the block and against the casing. The screw-spindle *k* is connected to the carbon block and insulated from the casing *i* and from the spring by means of the nut *l*. The spring *m* urges the carbon block towards the pole pieces *g*, and the nut *l* which holds it back, is adjusted by regulating the distance between the armature plate *e* and the pole pieces. The terminal screw *c* is insulated from the carbon block and from the casing and connected electrically with the armature plate *e* whence the carbon passes through the carbon elements and through the screw spindle to the terminal *d*.

In the modified construction shown in Figs. 3 and 4, the carbon block is connected by means of the spindle *k* to a metal yoke *n* which is insulated, for instance by mica washers, from the block as well as from the spindle. The diaphragm *b* and the armature plate *e* are secured to the down-turned ends of the yoke *n* which is held in a casing *i* as previously described. The terminal screw *c* is connected to the casing *i* and the current passes through the latter, through the spring *m* and through the yoke *n* to the armature plate and thence through the carbon elements to the terminal *d*.

In both constructions the armature plate *e* is substantially lozenge-shaped, as shown in Fig. 2, i. e., it tapers at both ends towards the connecting screw *h* where, owing to the reduced width of the plate, very little resistance will be offered to its vibratory movements. Thus a very sensitive microphone will be obtained.

In the case of smaller instruments, the microphone bar may be simplified as shown in Fig. 5 where the carbon electrodes are

enclosed in a casing *o* which differs from the casing *i* in that it is provided with end members which are bent twice to form supports for the diaphragm *b* and the plate *e*, these elements being secured direct to the casing. In this construction the supporting edges of the casing *o* are placed initially so that the armature plate *e* will be correctly positioned by the casing without readjustment.

10 Fig. 6 illustrates the employment of the microphone bar in a sound amplifier for use in connection with radio receivers.

The watch receiver *f* is hinged by means of a radial arm *p* which may be adapted to house a transformer. The cover *f'* of the receiver is slotted diametrically to admit the microphone bar to the receiver magnet relative to which the armature plate is adjusted by means of the hand wheel *l*. The microphone bar can be pulled away from the receiver in opposition to the magnetic attraction whenever inspection of the interior is required. The amplifier is connected to the radio set by means of wires *r* which lead 25 the received impulses through the watch receiver *f*. A local battery is connected to terminal studs *s* which lead the current through the microphone bar and through the primary coil of the transformer. Wires 30 *t* connect the bar with the battery and with the transformer. The secondary coil of the transformer is connected to terminal studs *u* to which the phones or a loud-speaker are also connected. The hinged arm *p* allows 35 the watch receiver and the microphone bar to be tilted backwards and forwards for regulating the gravitational distribution of the carbon granules in a manner known per se in connection with amplifiers of this type.

40 I claim:

1. In a magneto-microphonic relay of the character described, the combination with a watch-shaped receiver casing and its electro-magnet, of a bar-shaped microphone unit 45 adapted to bridge the receiver casing, and a combined vibratory armature plate and carbon electrode held in said microphone unit and adapted to retain the latter in position on the receiver casing merely by the mag-

netic attraction between the armature plate 50 and the receiver magnet.

2. The structure claimed in claim 1 including a casing of U-shaped cross-section enclosing the microphone unit and supporting it on the edge of the receiver casing 55 against the magnetic attraction, and means for adjusting the microphone unit within said casing to regulate the distance of the armature plate from the magnet poles.

3. In a magneto-microphonic relay of the 60 character described, the combination with a watch-shaped receiver casing and its electro-magnet, of a microphone casing of U-shaped cross-section bridging said receiver casing, a bar-shaped microphone unit having 65 a vibratory carbon electrode and being housed in said casing, a screw-spindle secured to the microphone unit and projecting through the back of the microphone casing, a blade spring arranged between the 70 microphone unit and its casing, a nut in the form of hand wheel arranged on said spindle outside the casing so as to co-operate with the spring for supporting the microphone unit in the casing, and a substantially 75 lozenge-shaped armature plate connected to the vibratory carbon electrode of the microphone unit and fastened to the latter by means of its tapering ends so that it faces the magnet poles and holds the microphone 80 unit in position on the receiver casing by the magnetic attraction.

4. A sound amplifier for radio receiving sets comprising a base, an arm hinged to said base so that it can be adjusted in a vertical plane, a watch receiver connected to said arm and fitted with a cover having a diametral slot, a bar-shaped microphone unit having a combined vibratory armature plate and carbon electrode, said microphone 90 unit being made to fit the slot in said cover, to bridge the casing and to be held in position thereon merely by the magnetic attraction between the armature plate and the receiver magnets, and means for regulating the position of the armature plate relative to the magnet poles.

CARL FREDERICK ADOLPH.
